(57) **CLAIM**

The ornamental design for a beverage cup, as shown and described.

DESCRIPTION

FIG. 1 is an isometric view of a beverage cup.

FIG. 2 is a front view of the beverage cup of FIG. 1.

FIG. 3 is a top view of the beverage cup of FIG. 1; and,

FIG. 4 is a bottom view of the beverage cup of FIG. 1. Portions of the beverage cup not shown in the drawings form no part of the claimed design. The broken lines depict a portion of the beverage cup that forms no part of the claimed design.
